UNITED STATES PATENT OFFICE.

LOUIS KOCJAN, OF CALUMET, MICHIGAN.

FIRE-ESCAPE.

1,397,640.

Specification of Letters Patent.

Patented Nov. 22, 1921.

Application filed May 16, 1921. Serial No. 469,876.

To all whom it may concern:

Be it known that I, LOUIS KOCJAN, a citizen of Jugo-Slavia, residing at Calumet, in the county of Houghton and State of Michigan, have invented certain new and useful Improvements in Fire-Escapes, of which the following is a specification.

This invention relates to certain new and useful improvements in fire escapes of that type embodying a car with means for mounting the same for vertical movement upon the outside of a dwelling in line with the superposed windows provided on the successive floors or stories of the dwelling.

The primary object of the invention is to coöperatively construct the car and its guiding and mounting means in a novel manner so that the car will be effectively guided in its vertical movements and whereby travel is combined with simplicity for enabling the device to meet the requirements for a successful commercial use.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a fragmentary front elevational view of a dwelling equipped with a fire escape constructed in accordance with the present invention,

Fig. 2 is a side elevational view of the device shown in Fig. 1,

Fig. 3 is a vertical sectional view taken along line III—III of Fig. 6,

Fig. 4 is a similar view taken upon line IV—IV of Fig. 6,

Fig. 5 is a horizontal sectional view taken upon line V—V of Fig. 4, and

Fig. 6 is a horizontal sectional view taken upon line VI—VI of Fig. 3.

Referring more in detail to the several views, the present invention embodies a fire escape including a car 5 mounted, as will presently become apparent, for vertical movement at the outside of a dwelling 6 so that a person may enter said car from any one of the superposed windows 7 provided in the several stories of said dwelling, when said car is located opposite said window. The car 5 preferably embodies a roof

and a floor connected in spaced relation and the connecting means includes a pair of corner posts 8 between which extends a foraminous wall 9 inclosing the sides and back of the car and leaving the front or inner portion of the car open for permitting ready entrance of persons thereinto, the foraminous nature of the car body enabling firemen and others to ascertain that the car is occupied if such be the case when said car is in an elevated condition.

At opposite sides of the windows 7 are mounted pairs of guide rails 9, the ends of which are inturned and fastened to the wall 70 of the dwelling as at 10 in any preferred manner. The outside rail of each pair slidably extends through one of the corner posts 8 of the car, while the other rod of each pair extends slidably through the roof 75 and floor of said car adjacent to one of said posts. Thus, one guide rail or rod 9 is exposed at each side of the car for being gripped by an occupant so as to prevent too rapid descent of the car when overloaded. 80

The car 5 is counterbalanced so as to normally be held in an elevated position by means of a flexible member 11 which is attached at one end to the roof of the car and which passes upwardly therefrom and 85 inwardly and around a guide pulley 12 which is suitably journaled in a bracket 13 fixed to the wall of the dwelling substantially midway between the pairs of guide rails 9. The flexible member 11 extends downwardly to a point adjacent the ground and has weights 14 suspended therefrom which are slightly heavier than the car 5.

By rigidly connecting the roof and floor of the car by corner posts of hollow form 95 and utilizing these posts as guides through which a guide rail slidably extends at each side of the car, a durable construction is provided wherein ordinary strains will be effectively taken care of.

In operation, and in case of a fire, a person may step into the car 5 from a window 7 if said car is opposite the same, while if the same is required to be lowered this may be effected by pulling upwardly upon the 105 flexible member 11. Upon stepping into the car the inner rail of either pair or the flexible member 11 may be grasped so as to prevent premature downward movement of the car and to prevent too rapid descent of the 110 latter, the weight of the person being sufficient to overcome the weights 14 for insur-

ing lowering of the person to the ground by gravity. As soon as the person reaches the ground, he or she simply lifts upwardly on the flexible member 11 so as to prevent 5 the weights 14 from returning the car to elevated position before complete exit of the person from the car. The flexible member 11 is then released and the weights immediately return the car to elevated position.

10 From the foregoing description it is believed the construction and operation as well as the advantages of the present invention will be readily understood and appreciated by those skilled in the art.

15 What is claimed as new is:—

A fire escape including guide rails adapted to be mounted in a vertical position at opposite sides of superposed windows of a dwelling, a car including roof and floor 20 members rigidly connected by means including corner posts having said guide rails slidably extending therethrough, further guide rails at opposite sides of the windows

inwardly of the first named guide rails and 25 slidably extending through the roof and floor members of the car with the portions of the same between the roof and floor members exposed, the sides and back of the car being inclosed by a foraminous wall and the corner posts and guide rails being located 30 at the front of the car adjacent the dwelling, the space between the corner posts being open, counterbalancing means for said car to normally hold the latter in an elevated position, said counterbalancing means including a flexible member weighted at one 35 end and having its other end attached to the roof of the car substantially centrally between the sides of the latter, and a pulley over which said flexible member passes, said 40 pulley being adapted to be mounted upon the wall of the dwelling substantially midway between said guide rails.

In testimony whereof I affix my signature.

LOUIS KOCJAN.
